CAN-BOXING MACHINE.

1,348,549.

Specification of Letters Patent.

Patented Aug. 3, 1920.

Application filed March 1, 1916. Serial No. 81,449.

To all whom it may concern:

Be it known that I, HAYWOOD G. DEWEY, a citizen of the United States, residing at Westminster, in the county of Carroll and State of Maryland, have invented certain new and useful Improvements in Can-Boxing Machines, of which the following is a specification, reference being had therein to the accompanying drawing.

10 This invention relates to boxing machines of a character adapted to assemble a supply of cans, cartons or the like, and to position such supply within a box or casing, whereby the latter is filled.

15 While the invention is designed primarily for the purpose of boxing cans, and while throughout the description, the term can or cans will be employed as designating the articles to be incased, it is to be borne in mind 20 that the invention is not limited in this particular, as the machine is equally susceptible of use for packaging articles of various characters.

The invention may be said to be along the same general line as that character of invention embodied in the patent to E. W. Cornell, No. 560,058, dated May 12, 1896, entitled can case filling machine, it being one of the primary objects of the present invention to generally improve upon the construction illustrated in the said patent, having in mind greater efficiency and more satisfactory results generally.

One of the objects of the present invention is to provide means whereby the box filling mechanism *per se* may be more easily and readily operated and preferably through the medium of treadle actuating means, whereby the hands of the operator are left 40 free for the feeding of the cans to the machine, the placing and removal of the box or case upon, or from, the box supporting part of the machine, etc., etc.

A further feature of the invention relates 45 in the provision of novel and improved ejector mechanism for the cans whereby the latter are readily inserted into the box or case, and with less expenditure of energy on the part of the operator.

50 It is also contemplated by the invention to provide novel and improved means for positively separating from the main can supply, that portion thereof to be ejected into position to be placed in the box, the

said means being of a character to readily move between adjacent cans in the separating operation, and without the danger of injuring or marring the label upon the cans, it being noted in this connection that the present machine is preferably of a character 60 to be coupled up directly with a can labeling machine at the discharge end thereof.

The invention further embodies novel and improved supporting means for the box or casing, having in view more particularly the 65 positioning and removal of the box from its position to receive the cans and in a manner resulting in considerable saving of time and with less likelihood of damage to the labels on the cans.

Still further the invention includes novel and improved means whereby the can filled case or box may be discharged from the machine.

Again the invention embraces means 75 whereby the actuating mechanism for the can ejecting means for filling the boxes is arranged at a position most accessible to the operator, and in this connection said actuating means is preferably arranged at 80 the front side of the machine or at that side where the labeled cans are fed into the machine and at a point adjacent the discharge position of the filled box. In this way, it is possible for the operator, without changing his position to operate the can ejecting or box filling mechanism, preferably with his foot, and with his hands position and cause the discharge of the can filled box 85 from the machine.

Still further improvements and novel details in the construction and arrangement of various parts will be more thoroughly appreciated from the description to follow, which, for a clear understanding of the invention is to be considered in connection with the accompanying drawings, which form a part hereof, and wherein is disclosed for the purpose of illustration, a convenient and satisfactory embodiment of 100 the invention, though it is to be borne in mind in this connection, that minor changes in arrangement or construction of parts may be resorted to without departing from the spirit of the invention.

105 In the drawings:—
Figure 1 is a front end elevation of the machine.

Fig. 2 is a top plan view.

Fig. 3 is a front side elevation.

Fig. 4 is a longitudinal section substantially on the line 4—4 of Fig. 2 looking in 5 the direction of the arrow.

Fig. 5 is a detail view of part of the treadle mechanism broken away.

Fig. 6 is a detail view of the discharge runway for the boxed cans.

- 10 With more particular reference to the drawings wherein like reference numerals refer to corresponding parts throughout the several views, a suitable supporting framework is provided, the same including 15 elongated longitudinally extending front side bars 1 and rear side bars 2 separated laterally from one another. Supported upon the bars 1 and 2 adjacent what may be termed the front end of the machine are 20 transversely extending bars 3 and 4, the said bars 3 and 4 being secured to the bars 1 and 2 in any desired manner and having suitable transverse brace members 5, whereby to reinforce and strengthen the same. 25 The bars 3 and 4 at the rear end thereof, are supported in any desired manner upon suitable legs or uprights 6 and 6^a respectively. The frame at its opposite or front end is supported preferably through the 30 medium of suitable legs or standards 7. A suitable chute 8 is provided at the front end of the machine, the same being supported upon the framework 3, 4, 5, the said chute having suitable internal partitions or 35 flanges 9, 10, 11 and 12. The chute is open at its top whereby to receive cans from a suitable runway extension 13 secured thereto in any desired manner and adapted for connection with the tail end of a can labeling machine. Connecting with the discharge end of the chute are a series of superimposed elongated pans or trays 14, 15 and 16, the same having at the outer edge, suitable can retaining flanges 14^a, 15^a and 16^a 40 and at their inner edges relatively short retaining flanges 14^b, the said flanges 14^b being cut-off whereby to provide for the movement of the cans laterally from off said pans into position to be boxed. The 45 pans or trays 14, 15 and 16 are supported from one another as by upright braces 17 and at the rear end thereof by a suitable casting or the like 18, which latter constitutes an abutment for limiting the downward movement of the cans along the runways provided by said pans or trays. The 50 said pans or trays, as will be seen from Fig. 1 of the drawing incline downwardly from the feed chute. The lowermost pan or tray 16, at the end thereof together with 55 the abutment 18 is of a width substantially equal to twice the length of the can, as indicated at 16^a, whereas the trays 14 and 15 are of a width throughout, substantially 60 equal to the height of the cans, with the re-

sult that when the cans are moved laterally from off the flangeless edge of the trays, the extension 16^a of the lowermost tray constitutes a support for the separated supply of cans which in this latter position, rest directly upon one another in vertical and horizontal rows.

19 is a suitable abutment projecting from the uppermost to the lowermost tray at the front edge of the extension 16^a of the lowermost tray, whereby as a series of rows of cans are moved from off the trays, they will be held in position by the co-operating abutments 18 and 19.

Positioned upon an offset part of the 80 abutment members 18 and 19 are suitable supporting plates 20 having mounted therein suitable retaining rods 21 separated from one another and forming the side walls of a can retaining skeleton frame. The supporting plates 20 have therein lateral slots, whereby by loosening the retaining bolts 22, the two series of side bars 21 may be relatively adjusted. The bars 21 are spaced vertically from one another whereby to provide 85 pockets for the reception of the outermost series of cans. The bottom of the said can retaining skeleton frame is preferably provided for by means of relatively flat bars 22^a having an angular projection 23 90 adjustably supported to the frame member 3 as by means of a bolt and slot connection. The bars 22^a at the point of connection with the flanges 23 are rounded as illustrated at 95 23^a and in the normal position of the bars 22^a they are preferably above the horizontal plane of the lowermost tray extension 16^a, whereby said bars constitute an effective 100 guide for the series of cans as delivered to the retaining skeleton frame by the ejecting apparatus about to be described. The horizontal position of the bars 22^a may be readily adjusted through the medium of the bolt and slot connection, and it will be observed that these bars are separated from 105 one another a sufficient distance to form receiving pockets for the lowermost series of cans, the cans readily riding over the rounded elbows of the bars 22^a and seating in said pockets as will be obvious.

110 It is desirable that means be provided for supporting the box in position to overlie the cans retained in the frame provided by the bars 21 and 22^a, and that this means be of a character to assist in the positioning of the box and removal of the same with the supported cans. In the illustrated embodiment of the invention, the box supporting means preferably takes the form of a plurality of separated tracks having a 115 base 25, and an upright relatively thin or narrow web 26 upon which the box is adapted to rest and slide. The tracks are slidably mounted at their base upon extending bars 28, for a purpose to be herein- 120 125 130

after more particularly referred to. Said bars 28 have depending bracket supports 29 secured for vertical adjustment to the frame members 1 and 2 as by pin and slot connections 30. The tracks 25-26 when properly adjusted afford a guide for the operator in placing the box over the cans supported by the retaining bars 21-22^a heretofore described, and because of the peculiar construction of supporting means for the box, it will be observed that the box whether empty or filled, will readily slide over the relatively narrow webs 26 of the tracks, and said tracks being separated, this will leave an unobstructed portion of the side of the box in contact with the tracks free for the engagement of the hand of the operator in the assembly or removal of the box.

20 The can ejecting mechanism for forcing a supply of cans from the trays or runways and in the position to be placed within the box or case to be filled, in the preferred embodiment of the invention illustrated, is constructed substantially as follows:—

31 are a series of ejecting members or plungers proper, the same preferably taking the form of blocks or leaves conveniently of wood and having at the inner edge thereof a reinforcing metallic plate 32. The plungers 31 at opposite edges are supported upon suitable brackets 33, the plungers 31 being separated from one another whereby to engage the ends of the cans at points above the flanges 14^a, 15^a and 16^a. The brackets 33 have intermediate the ends thereof, an apertured lug 34 adapted to receive a stub shaft 35 mounted upon the upper end of carrying levers 36. The engagement between the lugs 34 of the plunger brackets and the shaft 35 is a loose one, whereby to permit rocking movement of the brackets 34 and the plungers about said shaft 35. The carrying levers 36 at the lower end thereof are connected to suitable supports 37 sleeved upon a transversely extending shaft 38 mounted upon depending brackets 39 on the frame members 1 and 2. Suitable guide-ways for the levers 36, take the form of plates 39' secured to the upper surface of the bars 1 and 2, the said plates having a reduced portion 39^a at one edge thereof, whereby to receive the levers 36. Said inner edge of the plates at the enlarged ends thereof connecting with said reduced portion, form abutments 40 and 41 for limiting the forward and backward rocking movement of said levers 36 and the parts carried thereby. One or both of said abutments may have connected thereto a yieldable buffer, one of said buffers at the rear end of the plate being illustrated at 42. The plates 39' are adapted to be laterally adjusted through the medium of

the bolt and slot connections 43, whereby to take up any unnecessary play, and to at the same time, allow for the free swinging movement of the levers 36 therebetween.

As has been seen, the plungers 31 are supported, whereby to have free rocking movement about the bearings 35, means being provided to support the plungers and properly guide the same as moved forward or backward with the carrying levers 36. In this connection, a roller bearing 44 is provided upon the lower surface of the bottom plunger adjacent the forward edge and one side of the latter, said roller bearing being adapted to engage a suitable track comprising an upwardly inclined portion 45 connecting with a downwardly inclined portion 46 in turn connecting with a horizontally extending portion 47 in horizontal alinement with the bottom tray 16. In the normal position of these parts, as illustrated more particularly in Figs. 3 and 4, it will be observed that the carrying levers 36 are in contact with the buffer members 42, in which position the roller bearings 44 will be in engagement with the upwardly inclined portion of the track 45. Forward movement being imparted to the plungers, the latter are guided by the track which engages the roller bearing 44 to the end that the forward end of the plungers will first move upwardly about the pivotal support 35 and thence downwardly, and when the reinforced forward edge 32 of said plunger contacts with the ends of the cans, the plungers 31 will be in substantially a horizontal plane, and will be maintained in this plane for the remainder of the movement thereof in forcing the cans from the trays. It is of advantage to arrange the carrying levers 36 and roller engaging track substantially as illustrated, it having been found in practice that the cans are readily moved from off the trays with the least expenditure of exertion on the part of the operator, and the plungers 31 moving in a horizontal plane or substantially a horizontal plane after engaging the cans, and the engaging ends 32 of the plungers will be substantially free from any rocking or rubbing action on the ends of the can which might tend to tear or injure the labels should the same take the form of wrappers overlying the ends of the cans.

There is a further and important advantage in imparting to the forward end of the plungers 31, the upward and thence downward movement through the medium of the roller bearing 44 and track 45-46 and 47, namely the possibility of more readily separating the supply of cans to be boxed from the body of supply in the runways or trays and this without injuring the labels or wrappers for the cans. In the illustrated embodiment of the invention, the can separating

means preferably takes the form of a series of blades 50 secured to one edge of the plungers 31 through the medium of brackets 51 which latter are adjustably mounted through the medium of bolt and slot connections 52 with the arms 33^a of the bracket member 33. The blades 50 are preferably of sheet metal, whereby the same are springy or yieldable, and the position of these blades 5 10 may be accurately adjusted through the medium of the bolt and slot connections 52 just described. From a reference more particularly to Fig. 3, it will be observed that in the normal position of the plungers 31, the blades 50 connected therewith will assume a position at an upward inclination toward the free ends thereof or above the cans positioned in the runways or trays. When the roller bearing 44 engages the downwardly 15 inclined section 46 of the guide track, the free forward ends of the blades 50 are allowed to quickly fall downwardly, somewhat after the fashion of a shearing action with the result that said blades will readily engage in the space between the cans from the top surface thereof, thereby separating the supply of cans to be boxed from the main supply in the runway. The free ends of the blades when reaching the forward limit of 20 movement will engage in the space within the inner surface of the abutment member 19. The blades as illustrated are mounted directly upon the plungers or the supports therefor, with the result that the operation of the one part, will at the same time, impart movement to the other part.

While if desired, satisfactory results may be obtained by providing operating means for the plungers, such as a handle or the like 40 connected directly thereto, at the same time it is preferable, and desirable in the present instance, to provide treadle actuating means for the plungers, thus requiring less exertion on the part of the operator, and 45 permitting the same operator without a change of position to operate the plungers and at the same time assemble and remove the box or case which has been or is to be filled. With this in view, a suitable treadle 50 or foot engaging device 54 is provided adjacent the rear end of the front face of the machine, the said treadle being sleeved at its rear end upon a suitable shaft or pintle 55 secured to the framework of the machine 55 in any desired manner. The treadle 54 is guided at its free end by a suitable slotted plate 56 secured to one of the legs of the framework. 57 is a transversely extending shaft projecting between the frame members 1 and 2 and sleeved upon said shaft is a bell crank lever 58 loosely connected at one end in any desired manner with a suitable link 59 which latter is loosely connected at its lower end with a treadle 54 intermediate the 65 ends of the latter. The bell crank lever

58 at its opposite end is loosely connected to a horizontally extending reach rod or bar 60 having a sleeved engagement at its opposite end with a shaft 61 mounted upon an upward extension 62 of the lever supporting 70 brackets 37 heretofore described. Suitable spring members 63 connected at one end to suitable lugs 64 on the frame members 1 and 2, and at the opposite end to the swinging or rocking brackets or supports 37-62, 75 are provided to maintain the parts in normal position; that is to say to retain the treadle in elevated position, and the plungers in a position illustrated more particularly in Figs. 3 and 4. The spring is preferably adjustable at one end as illustrated at 65, whereby to regulate the tension thereof and in turn to regulate the return movement of the parts to normal position.

It has been found that when the case or 85 box has been filled with cans, the cans in the case lying snugly against the cans remaining in the retaining fingers 21-22^a, some little difficulty is encountered in separating the can filled case from the cans still 90 remaining in the fingers, and in order to obviate this, provision is made for moving the tracks 26 lengthwise whereby to separate the cans in the box from the cans remaining in the case. In the preferred embodiment of the invention, this mechanism preferably includes a lever 70 sleeved upon a shaft 71 supported in brackets 72 depending from the framework, said lever at its upper end pivotally connected with a link 100 73 which latter at its upper end has pivotal connection with a shaft 74 connected through the medium of brackets 75 with the base of the tracks 26. 76 is a reach rod having a pin and slot connection 77^a at one end with 105 the lower end of the lever 70 and having a loose engagement at its opposite end as at 77 with one of the rocker arms 36 for movement with the latter. It is obvious of course that the lever connections 70-73-76 may 110 be duplicated on opposite sides of the machine, one for each of the tracks which support the box. The actuating means for the tracks being connected to the rocker arms 36, it will be observed that the tracks like the 115 other movable parts of the machine are actuated by the foot treadle mechanism. As the rocker arms 36 are moved forwardly in the ejecting operation of the plungers 32, the reach rod 76 is moved forwardly until 120 reaching the end of the slot in said reach rod when the lever 70 will be moved about the pivot 71 thereby causing the tracks to move inwardly along the box, the cans together with the members 22^a, 23^a and 23 constituting an abutment for preventing inward movement of the box with the tracks. As the treadle is released whereby to allow the spring 63 to return the rocker arms 36 with the plungers rearwardly, this will result in 125 130

a reverse movement of the tracks because of the lever connections with the rocker arm, and this reverse movement of the tracks with the case of filled cans, thereby separates the cans remaining in the cage or supporting fingers.

At the discharge end of the machine adjacent the rear end of the box separating tracks is a suitable discharging member for 10 the can filled box or case, said discharging member preferably taking the form of an elongated transversely extending frame 66 having suitable side flanges 67 and rollers 68 having bearings at opposite ends in said 15 side flanges. The platform 66 is preferably detachably supported upon the frame members 1 and 2 as through the medium of bolts 66^a and when thus positioned, the rollers at one end will be immediately adjacent and 20 below the terminals 25^a of the box supporting tracks, which said track terminals are rounded as illustrated whereby the box may be readily tilted about said rounded terminals as a fulcrum and positioned with the 25 bottom of the case resting upon the rollers and the open end thereof disposed uppermost. When in engagement with the rollers the box may be readily moved over the same and into a position on the base of the platform at the discharge end thereof to be removed to a suitable place of deposit.

The operation may be reviewed as follows:—

Assuming that the present machine is 35 coupled with a can labeling or wrapping machine, the labeled or wrapped cans are allowed to travel along the runway 13 into the feed chute 8, the cans rolling down the flanges 12 into contact with the base of the 40 lowermost tray 16, entirely filling said tray as well as the bottom of the chute 8. Thereupon, succeeding cans will travel over the flanges 11 and 10 and thence into the second tray 15 entirely filling the same. Thereafter, 45 succeeding cans will roll directly into the topmost runway 14. The trays being completely filled, the operator with his foot, engages the treadle and presses downwardly, thereby moving the bell crank lever 58 about 50 the shaft support 57, the opposite end of said lever imparting longitudinal movement to the reach bar 60, which latter being connected with the shaft 61 and rock support 39, will cause the carrier levers 36 to move 55 the plungers 31 forwardly. The plungers 31 having a loose bearing at 35 will be caused by the roller engagement with the cam track 45—46 and 47 to move first upwardly and thence downwardly whereby the 60 separating blades 50 will be moved laterally with respect to the longitudinal axis of the cans and readily separate a series of cans from the supply of cans in the runway. The continued movement of the carrier levers 36

will cause the plungers and separating blades 65 to move in a substantially horizontal plane throughout when in contact with the cans, and because of the peculiar position of the levers 36 and associated parts, the engaging end of the plungers 31 will maintain the 70 original contact with the ends of the cans thus overcoming any rubbing tendency, which might injure any end labels or wrappers on the cans. The movement of the carrier levers 36 being limited by the stops 75 40—41 on the lever guide 39, it will be found that the forward movement of the plungers is sufficient to push the first tier of cans out into the space between the runway and the retaining bars 21—22^a. The trays 80 or runways being again completely filled, the treadle is again actuated with the result that the plungers will push out a second tier of cans, this action being repeated until there are two tiers of cans supported by the bars 85 21—22^a. An empty box is then slid along the runway bars 26 and over the two tiers of cans supported by the skeleton frame formed by the fingers 21—22^a, the bars 26 supporting the weight of the box and guiding the same clear of the labels at the bottom. The treadle is thereupon actuated two more times, allowing the runways or trays to again completely fill after each action of the treadle, thereby causing the plungers in 95 the ejecting movement of the cans to push the filled box off of the supporting bars 21—22^a. The cans in the case are separated from the cans remaining in the cage or supporting fingers by the slideable movement of 100 the case due to the movement of the case supporting tracks, when the can filled box may be readily slid by the operator along the runway bars and coming in contact with the rounded end 25^a of said bars will tilt 105 whereby the box will be positioned with the open end uppermost and the bottom resting upon the gravity rollers of the discharge runway.

What is claimed as new is:—

1. In a can boxing machine, the combination of a runway for cans to be boxed, means for ejecting a series of cans from the runway into boxing position comprising a plunger adapted to engage the series of cans, 115 and means for moving said ejecting means whereby a substantially curvilinear movement of the same is converted into a substantially horizontal movement thereof.

2. In a can boxing machine, the combination of a runway for cans to be boxed, means for ejecting a series of cans from the runway into boxing position comprising a plunger adapted to engage the series of cans, 120 and means for moving said ejecting means whereby a substantially curvilinear movement of the same is converted into a substantially horizontal movement thereof,

which horizontal movement is maintained throughout the ejecting movement of the plunger.

3. In a machine of the character described, 5 the combination of a series of superposed runways for cans to be boxed, and means for simultaneously ejecting a series of cans from each runway into position to be boxed, said ejecting means comprising a plurality 10 of connected plungers adapted to engage one end of the cans, and means for imparting to the plungers a substantially curvilinear movement and thence a horizontal movement which horizontal movement is 15 maintained while the plungers are in contact with the cans.

4. In a machine of the character described, the combination of a runway along which cans are adapted to roll, a stop to limit the 20 movement of the cans along the runway, and means for ejecting a series of cans laterally from off said runway into boxing position comprising a plunger adapted to engage the ends of the cans, a pivotally mounted carrier 25 for the plunger, a loose engagement between the carrier and plunger, means for imparting movement to the carrier, and associated cam means for guiding the plunger whereby the engaging end of the same will 30 be moved first upwardly and thence downwardly into contacting engagement with the cans.

5. In a machine of the character described, the combination of a runway along which 35 cans are adapted to roll, a stop to limit the movement of the cans along the runway, and means for ejecting a series of cans laterally from off said runway into boxing position comprising a plunger adapted to engage the 40 ends of the cans, a pivotally mounted carrier for the plunger, a loose engagement between the carrier and plunger, means for imparting movement to the carrier, a cam guide-way, and a roller bearing connected to the 45 plunger and adapted to engage the guide-way for guiding the plunger whereby the engaging end of the same will be moved first upwardly and thence downwardly into contacting engagement with the cans, said guiding 50 means being constructed and arranged whereby the plunger when in contact with the cans will be maintained against rubbing engagement therewith.

6. In a machine of the character described, 55 the combination of a runway along which cans are adapted to roll, a stop to limit the movement of the cans along the runway, and means for ejecting a series of cans laterally from off said runway into boxing position 60 comprising a plunger adapted to engage the ends of the cans, a pivotally mounted carrier for the plunger, a loose engagement between the carrier and plunger, can-separating means movable with the plunger, 65 means for imparting movement to the car-

rier, a guide-way for the free end of the plunger, said guide-way having a raised portion in advance of the can engaging position of the plunger, whereby said can-separating means will in the further movement of the 70 plunger be caused to move downward between cans.

7. In a machine of the character described, the combination of a runway along which cans are adapted to roll, a stop to limit the 75 movement of the cans along the runway, and means for ejecting a series of cans laterally from off said runway into boxing position comprising a plunger adapted to engage the ends of the cans, a pivotally mounted carrier 80 for the plunger, a can separating blade mounted for movement with the plunger, means for imparting movement to the carrier, a guide-way for the free end of the plunger, said guide-way having a down- 85 wardly inclined part immediately in advance of the can engaging position of the plunger, thereby permitting the blade to move downward between the peripheries of adjacent cans.

8. In a machine of the character described, the combination of a runway along which cans are adapted to roll, a stop to limit the movement of the cans along the runway, and means for ejecting a series of cans laterally 95 from off said runway into boxing position comprising a plunger adapted to engage the ends of the cans, a carrier for the plunger, a can-separating blade carried by the plunger, means for imparting movement to the 100 carrier, a guide-way for the free end of the plunger, said guide-way having a down- 105 wardly inclined part immediately in advance of the can engaging position of the plunger, and a roller bearing at the free end of the plunger to engage said guide-way, as the plunger is moved by the carrier whereby to 110 guide the blade from a position above the cans to a position between adjacent cans.

9. In a machine of the character described, 110 the combination of a runway along which cans are adapted to roll, a stop to limit the movement of the cans along the runway, and means for ejecting a series of cans laterally 115 from off said runway into boxing position comprising a plunger adapted to engage the ends of the cans, a carrier for the plunger, a can-separating blade carried by the plunger, means for imparting movement to the carrier, a guide-way for the free end of 120 the plunger, said guide-way having an upwardly inclined part connecting with a downwardly inclined part, which latter connects with a horizontal part, whereby the blade in the movement of the plunger will 125 first be raised above the cans and thereafter moved downwardly between two adjacent cans.

10. In a machine of the character described, the combination of a runway along 130

- which cans are adapted to roll, a stop to limit the movement of the cans along the runway, and means for ejecting a series of cans laterally from off said runway into boxing position comprising a plunger adapted to engage the ends of the cans, a pivotally mounted carrier for the plunger, a loose engagement between the carrier and plunger, means for imparting movement to the carrier, a guide-way for the free end of the plunger, said guide-way having an upwardly inclined part connecting with a downwardly inclined part, which latter connects with the horizontal part, and a roller bearing at the free end of plunger to engage said guide-way, whereby the stop in the movement of the plunger will be caused to first rise above the cans and thereafter move downwardly between the cans.
11. In a machine of the character described, the combination of a runway along which cans are adapted to roll, a stop to limit the movement of the cans along the runway, and means for ejecting a series of cans laterally from off said runway into boxing position comprising a plunger adapted to engage the ends of the cans, a pivotally mounted carrier for the plunger, a loose engagement between the carrier and plunger, means for imparting movement to the carrier, an irregular guide-way for the plunger, and means at the free end of the plunger to engage the guide-way, and a can stop carried by the plunger and projecting forwardly thereof to engage between said series of cans and the supply of cans in the runway.
12. In a machine of the character described, the combination of a runway along which cans are adapted to roll, a stop to limit the movement of the cans along the runway, and means for ejecting a series of cans laterally from off said runway into boxing position comprising a plunger adapted to engage the ends of the cans, a pivotally mounted carrier for the plunger, a loose engagement between the carrier and plunger, means for imparting movement to the carrier, a guide-way for the free end of the plunger, said guide-way having a raised portion in advance of the can engaging position of the plunger, and a can separating blade carried with and projecting forwardly of the free end of the plunger.
13. In a machine of the character described, the combination of a runway along which cans are adapted to roll, a stop to limit the movement of the cans along the runway, and means for ejecting a series of cans laterally from off said runway into boxing position comprising a plunger adapted to engage the ends of the cans, a pivotally mounted carrier for the plunger, a loose engagement between the carrier and plunger, means for imparting
- movement to the carrier, a guide-way for the free end of the plunger, said guide-way having an upwardly inclined part connecting with a downwardly inclined part, which latter connects with a horizontal part, and a can separating blade carried by the plunger and projecting forwardly therebeyond.
14. In a can boxing machine, the combination of a series of superposed runways for cans to be boxed, and ejecting means to separate a series of cans from each runway into position to be boxed, said means comprising a plurality of connected plungers adapted to engage one end of the cans, a lever support for the plungers having a loose engagement with the rear end of the connected plungers, means for actuating said lever, a cam guide-way, means on the plungers to engage the cam guideway whereby to guide the plungers while in contact with the cans, and can separating blades, one for each plunger projecting forwardly of the latter, the said blades being caused to move by the cam guideway first upwardly above then downwardly between the cans to separate the latter.
15. In a can boxing machine, the combination of a runway for cans to be boxed, and means for separating a series of cans from the supply in the runway whereby said series may be moved laterally from the runway into boxing position, said means including an elongated blade, and means for moving said blade longitudinally and thence laterally of the length of the cans between adjacent cans.
16. In a can boxing machine, the combination of a horizontally disposed runway for cans to be boxed, and means for separating a series of cans from the supply in the runway, whereby said series may be moved laterally from the runway into boxing position, said means including an elongated blade, and means whereby the blade is caused to move downwardly between the peripheries of adjacent cans.
17. In a can boxing machine, the combination of a horizontally disposed runway for cans to be boxed, and means for separating a series of cans from the supply in the runway, whereby said series may be moved laterally from the runway into boxing position, said means including an elongated blade, and means for causing the same to move downwardly and thence horizontally between adjacent cans.
18. In a can boxing machine, the combination of a series of superimposed runways for cans, and means for separating a series of cans in each runway from the supply of cans in said runway whereby the plurality of series of cans may be ejected from the runway, said separating means including a series of elongated blades, one for each runway, a carrier lever pivoted at its lower end,

- a bracket support for the blades loosely mounted on the lever, means for imparting movement to the lever, a cam track, and a bearing member movable with the blades to engage the cam track, whereby the blades first move upwardly above the cans and thence downwardly between the cans.
19. In a can boxing machine, the combination of a series of superimposed runways for cans, and means for separating a series of cans in each runway from the supply of cans in said runway whereby a plurality of series of cans may be ejected from the runway, said separating means including a series of elongated blades, one for each runway, a carrier lever pivoted at its lower end, a bracket support for the blades loosely mounted on the lever, means for imparting movement to the lever, a track having an upwardly inclined portion, and a roller bearing connected with the blades for movement therewith adapted to elevate the blades above the cans, and thereafter to permit the blades to move into a position between adjacent cans.
20. In a can boxing machine, the combination of means for supporting a series of cans in position to be boxed, and a box support including oppositely disposed longitudinally extending guides separated from one another by an unobstructed space, said guides being arranged below said means and spaced therefrom whereby to constitute a guide for positioning the box over the series of cans, and means for moving the can filled box lengthwise of said box support.
21. In a can boxing machine, the combination of means for supporting a series of cans in position to be boxed, a box support arranged below said means and extending a considerable distance therebeyond, said support comprising a pair of angle bars, with an edge disposed uppermost, and with the space between said bars substantially unobstructed, whereby the box may readily slide longitudinally of the bars under the action of the hand engaging the box in said unobstructed space, and means for imparting bodily movement to said bars.
22. In a can boxing machine, the combination of means for supporting a series of cans in position to be boxed, a box support arranged below said means and extending a considerable distance therebeyond, said support comprising a pair of angle bars, with an edge disposed uppermost, and with the space between said bars substantially unobstructed, whereby the box may readily slide longitudinally of the bars under the action of the hand engaging the box in said unobstructed space, and a series of elongated rollers of substantially the length of the box, said rollers being arranged in close association and extending longitudinally of said bars at a point beyond the same and adapted to freely rotate in a direction transversely of said bars.
23. In a can boxing machine, the combination of a series of superimposed spaced can runways, laterally extending side and bottom bars forming a skeleton frame to receive a series of cans from said runways, said bottom bars being separated from one another to form receiving pockets for the lowermost series of cans, and said bars normally occupying a plane above the horizontal plane of the bottom runway.
24. In a can boxing machine, the combination of means for supporting a series of cans in position to be boxed, and a box support arranged below said means and spaced therefrom whereby to constitute a guide for positioning the box over the series of cans, and means for moving said box support longitudinally.
25. In a machine of the character described, the combination of means for supporting a plurality of series of cans in position to be boxed, a box support arranged below said means and having an extension beyond said means, said support comprising spaced bars whereby a box may be placed with one side on said bars and moved longitudinally along the same to position the open end of the box over said cans, and means for lengthwise moving said box support.
26. In a machine of the character described, the combination of means for supporting a plurality of series of cans in position to be boxed, a box support arranged below said means and having an extension beyond said means, said support comprising spaced bars whereby a box may be placed with one side on said bars and moved longitudinally along the same to position the open end of the box over said cans, and means for seating the cans in said box and for moving the box with the cans along the extension of the runway, and means for lengthwise moving said runway.
27. In a can boxing machine, the combination of a series of superimposed can runways, a box support, a can retaining cage, can ejecting means to force the cans from the runway into said can retaining cage, and means movable with and controlled by the can ejecting means for moving said box support lengthwise in opposite directions.
28. In a can boxing machine, the combination of an elongated inclined runway adapted to permit cans to roll along the same, ejector mechanism for a forward series of cans, and means operatively associated with said ejector mechanism for separating said forward series of cans from the supply of cans in the runway including a member adapted to move upwardly into a position above the cans and thence downwardly between the periphery of adjacent

cans and remain in can separating position during the ejecting operation.

29. In a can boxing machine, the combination of an elongated runway for cans, 5 ejecting mechanism for moving the cans transversely from said runway, a skeleton frame to receive said ejected cans, said frame comprising side bars spaced vertically from one another and bottom bars spaced 10 horizontally from one another, the cans being adapted to fit within the recesses between the bars, and means whereby the side bars may be adjusted laterally relative to one another, and means whereby the bottom 15 bars may be adjusted vertically.

30. In a can boxing machine, the combination of a runway for cans, transversely movable ejecting mechanism, and supporting means for a box to receive the ejected 20 cans, said supporting means comprising a pair of spaced guide rails extending transversely of the runway, and means for moving said rails longitudinally.

31. In a can boxing machine, the combination of a can runway, ejecting mechanism movable transversely relative to the runway, a frame to receive the ejected cans, 25 said frame being adapted also to receive a box in which the cans are to be placed, a support for the box, and means for imparting 30 relative longitudinal movement between said frame and box support.

32. In a can boxing machine, the combination of means for supporting a series 35 of cans in position to be boxed, and a box support arranged adjacent said means and projecting rearwardly therebeyond whereby to constitute a guide for positioning the box over the series of cans, and means for 40 moving said box support longitudinally.

33. In a can boxing machine, the combination of means for supporting a series 45 of cans in position to be boxed, and a box support projecting rearwardly from said means whereby to constitute a guide for positioning the box over the series of cans, and means whereby said box support may be moved longitudinally.

34. In a can boxing machine, the combination of means for supporting a series 50 of cans in position to be boxed, and a box platform arranged below said means adapted to receive and guide the box over the

series of cans, and means for bodily moving said platform. 55

35. In a can boxing machine, the combination of a can runway, ejecting mechanism moving transversely relative to the runway, a support to receive the ejected cans, a box support and means for imparting relative longitudinal movement between 60 said box support and can support, and a laterally extending discharge runway for the boxed cans.

36. In a can boxing machine, the combination of means for supporting a series of cans in position to be boxed, a box support arranged below said means and spaced therefrom whereby to constitute a guide for 65 positioning the box over the series of 70 cans, and means for moving said box support bodily toward the cans.

37. In a can boxing machine, the combination of a series of superimposed runways for cans to be boxed, can ejecting 75 means, said means comprising a plurality of connected plungers adapted to engage one end of the cans, and means for separating said series of cans from the supply in the runways, comprising elongated blades 80 operatively associated with the plungers, and adapted to bodily move from a position above the cans downward between the cans.

38. In a can boxing machine, the combination of a horizontally disposed runway for cans to be boxed, means for separating a series of cans from the supply in the runway, plunger means for moving said series laterally from the runway into boxing position, said separating means including an elongated blade, said blade being operatively connected for movement as the plunger moves, and adapted to move from a position above the cans downwardly between the periphery of adjacent cans, a treadle, and connecting mechanism between the treadle and plunger means. 95

In testimony whereof I hereunto affix my signature in the presence of two witnesses. 100
